J. N. CHADWICK

LEVEL

Filed Aug. 8, 1923

UNITED STATES PATENT OFFICE.

JOHN N. CHADWICK, OF CAMDEN, NEW JERSEY, ASSIGNOR OF ONE-HALF TO EMERSON McDODDIBNS, OF CAMDEN, NEW JERSEY.

LEVEL.

Application filed August 8, 1923. Serial No. 656,409.

To all whom it may concern:

Be it known that I, JOHN N. CHADWICK, a citizen of the United States, residing in the city and county of Camden, State of New Jersey, have invented a new and useful Level, of which the following is a specification.

My invention relates to a novel construction of a levelling device, and more particularly to means for enabling the degrees of inclination of various objects to be readily ascertained and to be visible when desired upon actuating a push button to close the circuit of a small incandescent lamp positioned in proximity to the indicating devices, and comprises a plurality of transparent dials having graduations thereon and hands or pointers visible at the exterior of each of said dials and coacting therewith, said pointers being actuated by gravity and their position being ascertained from a light chamber formed within the level for the reception of an incandescent light, which is lighted when desired by said push button.

It further consists of a novel construction of a level having a passage therein for containing electrical connections and a transverse bottom chamber containing the electric light and its battery, the outer walls of said chamber being transparent and the weighted hands or pointers being located preferably at the exterior of the transparent walls and mounted upon a shaft common to both pointers and located within a tube or sleeve which may be secured at its ends in said transparent walls.

It further consists of other novel features of construction, all as will be hereinafter fully set forth.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a level embodying my invention.

Figure 2 represents a section on line 2—2
Figure 3.

Figure 3 represents a section on line 3—3
Figure 2.

Figure 4 represents a section on line 4—4
Figure 2.

Figures 5 and 6 represent a modification.
Similar numerals of reference indicate corresponding parts.

Referring to the drawings.

1 designates my novel construction of level, the same comprising a body portion 2, which has the transverse drum 3 therein at whose outer ends are the walls 4 which are transparent and provided with graduations as will be understood from Figures 1 and 2.

5 designates a sleeve, which is centrally located within the transverse drum or chamber 3, and whose ends are supported in the walls 4, within which sleeve freely revolves the shaft 6 the outer ends of which are threaded for the reception of nuts 7, whereby the hands or pointers 8 are secured in position, it being understood that the sleeve 5 is stationary, and that the shaft 6 and pointers 8 can move or oscillate as a unit, the shaft 6 freely rotating in the sleeve 5 and the pointers 8 being weighted at their bottom ends, as at 8^x and always being in a pendant position or vertical, no matter what inclination the level 2 may assume.

9 designates a vertical passage in the body of the level, which communicates with the bottom passage 10, containing the battery 11, to which is connected the small incandescent light 12. 13 and 14 designate the electrical connections which form the electrical circuit to the battery 11, said circuit being opened and closed by the push button 15, which latter as well as the lamp and battery may be of any conventional construction and need not be described in detail.

The inner end of the battery casing 11 may extend through the hole 16 in the drum 3, and thus lock the latter in position. The length of the sleeve 5 is such that when the nuts 7 are tightened, all the parts are securely and accurately held in assembled position. It will be evident that the outer peripheries of the walls 4 may be secured to the contiguous ends of the drum 3, if desired by any suitable means and that a level con-

structed in accordance with my invention will be durable, accurate and reliable and the readings can be ascertained from either side and will be readily visible at all times.

5 It will further be apparent that my device can be utilized at night, since the electric light appliance renders the readings visible at a distance of several feet and since the light is only in operation when in use or when the push button is depressed, it will be apparent that there is no undue drain upon the battery 11.

10 It will further be apparent that by my novel invention a very quick and accurate movement will be imparted to the pointers 8, since the same are vertical under all conditions and by the employment of my device I am enabled to determine any degree of inclination, as well as the horizontal and 15 vertical status of any object to which the device may be applied.

15 In Figures 5 and 6, I have shown a ring 16, having the pointed ends of the horizontal expansion bar 17 secured therein, from 20 which the weighted pointers 8 are suspended on the screws 19, the washers 18 being interposed between the pointers 8 and the bar 17. The push button 20 in Figures 5 and 6, actuates the push rod 21, which 25 closes the circuit by its contact with the battery button 22 of the battery 23, the light being indicated at 24. The transparent material 4, seen in all the figures is preferably celluloid.

30 35 It will now be apparent that I have devised a novel and useful level, which embodies the features of advantage enumerated as desirable in the statement of the invention and the above description, and 40 while I have, in the present instance, shown and described a preferred embodiment thereof which will give in practice satisfactory and reliable results, it is to be understood that such embodiment is susceptible of modification in various particulars 45

without departing from the spirit or scope of the invention or sacrificing any of its advantages.

Having thus described my invention, what I claim as new and desire to secure by Letters Patent, is:—

1. In a device of the character stated, a body, a drum to be illuminated disposed transversely of said body and adapted to support a level, the drum side wall being apertured entirely therethrough and said body having a substantially longitudinal passage therein in register with the drum aperture, a casing enclosing a battery arranged in said passage and protruding through the drum aperture into said drum to interlock with the latter, a light bulb within said drum carried by said battery casing, a push button located upon said body, and an electrical connection between the battery and said push button.

2. In a device of the character stated, a body, a drum to be illuminated disposed transversely of said body, and adapted to support a level, the drum side wall being apertured entirely therethrough and said body having a substantially longitudinal passage therein in register with the drum aperture, and having a substantially vertical passage communicating with the first mentioned passage, a casing enclosing a battery arranged in said longitudinal passage and protruding through the drum aperture into said drum to interlock with the latter, a light bulb within said drum carried by said battery casing, a push button located upon said body above the vertical passage and an electrical connection between the battery and said push button which connection is arranged in said vertical passage.

JOHN N. CHADWICK.
